UNITED STATES PATENT OFFICE.

LOUIS KOSSUTH JOHNSON AND ABBOT AUGUSTUS LOW, OF NEW YORK, N. Y.,
ASSIGNORS TO THE ALDEN TYPE MACHINE COMPANY, OF SAME PLACE.

TYPE-SETTING APPARATUS.

SPECIFICATION forming part of Letters Patent No. 650,398, dated May 29, 1900.

Application filed July 8, 1898. Serial No. 685,895. (No model.)

To all whom it may concern:

Be it known that we, LOUIS KOSSUTH JOHNSON and ABBOT AUGUSTUS LOW, citizens of the United States, residing in the city of New York, borough of Brooklyn, in the county of Kings and State of New York, have invented certain new and useful Improvements in Type-Setting Apparatus, of which the following is a specification sufficient to enable others skilled in the art to which the invention appertains to make and use the same.

Our improvements relate to compositors' type-cases in which the types are arranged in vertical channels, from the lower ends of which they are forwarded automatically by a suitable pusher-blade upon the withdrawal of types previously advanced.

The invention consists in the special construction and arrangement of parts hereinafter described and claimed.

In the accompanying drawings, Figure 1 is a front elevation of a case, the central portion being broken away; Fig. 2, a horizontal section on plane of line 2 2, Fig. 7. Fig. 3 is a plan upon plane of line 3 3, Fig. 7. Fig. 4 is a side elevation. Figs. 5 and 6 show elevations of opposite halves of the holder. Fig. 7 is a vertical sectional elevation through the plane of one of the type-containing channels. Fig. 8 is a section on plane of line 8 8, Fig. 7. Figs. 9 and 10 are detail views of the pusher.

C represents the type-containing channel. H is the holder, into which the lower end of the type-containing channel C is inserted when it is desired to use the type-containing channel in the setter-case. The lower ends of the holders H fit into sockets s, formed in the edge of the table T, said sockets s being open in front.

U are the uprights, supporting the rod R, to which the loops L are pivotally supported, said loops L securing the upper ends of the channels, as in the application for patent, Serial No. 680,102, filed May 9, 1898, last filed by us. The upper ends of the channels C are also supported by a back rest B, attached to the standards U. The standards U also support between them the spacing and locking bar S. This bar S is formed with a series of tongues s', which fit in between the channels above the holders, as will be seen more clearly by

reference to Fig. 3. These tongues also bear upon the upper edges of the holders and prevent vertical movement of said holders and channels, the latter being coupled to the holders by latches c, heretofore used by us. 55

The channels and holders are held against forward movement by a series of spring-clamps P, mounted upon the bar S. This is preferably accomplished by pivotally supporting the arms p upon the pins p', projecting upward from the bar S, and by inserting spiral springs p² between the rear ends of said arms p, the forward ends of said arms being adapted to engage with and hold the 65 spine of the channel, which latter may be grooved or indented to receive the jaws of the clamps. These clamps P, while holding the channels firmly in position under ordinary conditions, are adapted to release the lower 70 end of a channel should the pusher encounter undue resistance, thereby preventing breakage.

The type-forwarder F consists of a comparatively-thin high blade of sheet metal secured 75 to a reciprocator D, actuated by the pitmen E, as heretofore described by us. The forwarding-blade F is made of maximum height in practice and is then reduced in height to meet the requirements of the different types 80 and channels.

The recesses s for the tenons of the holders H extend below the path of the pusher-blade F, so that the latter practically travels in a groove in the table T, the pusher-blade being 85 supported on one side by the side wall of said groove and on the other by the inner side of the holder. A flat metallic spring G is arranged upon the front of the table T below each recess s, the upper end of the spring extending slightly above the floor of the recess, so that when the holder is in place the spring G will bear against the front edge of the tenon h, thereby sustaining the holder in position 90 under ordinary conditions, but yielding sufficiently in case of any obstruction or irregularity of the pusher to avoid breakage. These springs G are preferably mounted adjustably upon the front of the table, and this may be accomplished by the use of various mechanical expedients. In the drawings the springs G are shown as slotted longitudinally and se- 95 100

cured to the table by means of set-screws *g*, which admit of their being raised and lowered.

What we claim as our invention, and desire to secure by Letters Patent, is—

- 5 1. In a compositor's type-case substantially such as described, the combination of the supporting-table *T*, formed with the open sockets *s*, the channel-holders *H*, and the spacing-bar *S*, arranged to hold the said holders against 10 vertical movement, substantially in the manner and for the purpose described.
2. In a compositor's type-case substantially such as described, the combination of the supporting-table *T*, having the open sockets *s*, the type-forwarding blade *F*, the type-holder *H*, the type-channel *C*, and the clamps *P*, engaging with the spine of the channel for the 15 purpose and substantially in the manner described.
- 20 3. In a compositor's type-case substantially such as described, the combination with the supporting-table *T*, having the open recesses *s*, the type-forwarding blade *F*, the type-holder *H*, the type-channel *C*, the spacing-bar 25 *S*, and the clamps *P*, consisting of the arms *p*, having the spiral spring *p'*, inserted between their rear ends and adapted to engage the spine of the channel, substantially in the manner and for the purpose described.
- 25 4. In a compositor's type-case substantially such as described, the combination of the sup-

porting-table *T*, formed with the open recesses *s*, the type-forwarder *F*, the type-holder *H*, the type-channel *C*, the spacing-bar *S*, formed with the tongues *s'*, entering between the 35 exterior walls of the channels, and bearing against the upper edges of the holders, and the clamps *P*, for engaging with the spines of the channels, the whole arranged and operating substantially in the manner and for the 40 purpose described.

5. In a compositor's type-case substantially such as described, the combination of the supporting-table *T*, formed with the open recesses *s*, the type-forwarders *F*, the channel-holders 45 *H*, the channels *C*, and the springs *G*, arranged and operating substantially in the manner and for the purpose described.

6. In a compositor's type-case substantially such as described, the combination of the supporting-table *T*, formed with the recesses *s*, the type-forwarders *F*, the channel-holders 50 *H*, the channels *C*, the springs *G*, for bearing upon the front of the holders *H*, and the clamps *P*, for engaging with the spine of the 55 channels substantially in the manner and for the purpose described.

LOUIS KOSSUTH JOHNSON.
ABBOT AUGUSTUS LOW.
